UNITED STATES PATENT OFFICE.

NATHAN M. LOWER, OF SCHENECTADY, NEW YORK, ASSIGNOR TO LOCOMOTIVE STOKER COMPANY, OF PITTSBURGH, PENNSYLVANIA, A CORPORATION OF PENNSYLVANIA.

LOCOMOTIVE-TENDER.

1,256,486.

Specification of Letters Patent. Patented Feb. 12, 1918.

Application filed January 15, 1917. Serial No. 142,475.

To all whom it may concern:

Be it known that I, NATHAN M. LOWER, a citizen of the United States, and resident of Schenectady, county of Schenectady, and 5 State of New York, have invented certain new and useful Improvements in Locomotive-Tenders, of which the following is a specification, and which are illustrated in the accompanying drawings, forming a part 10 thereof.

The invention relates to locomotive tenders in which there is provided a fuel bin; its object being to provide improved means 15 for advancing the fuel to the shoveling platform, where it will be within easy reach of the fireman. It consists in providing such tender with one or more screw conveyers located immediately above the fuel-supporting walls of the bin, and with power means 20 for operating such screw or screws.

In the accompanying drawings—

Figure 1 is a detail plan view of the fuel bin of a tender;

Fig. 2 is a detail vertical longitudinal section thereof, partly in elevation; and

Figs. 3 and 4 are details of the driving gear for operating the conveyer screws.

The tender shown is of that type in which the fuel bin is provided with an inclined 25 slope sheet at its rearward end, and is supplemented by a fuel-carrying deck back of the bin proper, but the invention is applicable to tenders provided with bins of different configuration and without a supplemental 30 deck.

The side walls of the fuel bin are represented at 10, 11, its bottom is shown at 12, and its slope sheet at 13. At 14 there is 35 shown a fuel deck extending backwardly from the upper end of the slope sheet and provided with a vertical back wall 15. The fuel is supported by the floor 12, the slope sheet 13, and the deck floor 14. Mounted upon each of these supporting floors are 40 screw conveyers 16, 17, 18; as illustrated in Fig. 1 four of each of these conveyers being shown. As many may be provided as may be deemed advisable. These conveyers are of the usual form, each comprising a shaft 45 on which is mounted a spiral flange. The shaft of each conveyer is journaled in one or more brackets rising from the fuel-supporting wall with which the conveyer is associated, and for convenience in driving the

conveyers of each set may be connected by 55 means of universal joints or by means of simple gearing.

As shown, the rearward end of the shaft of the conveyer 18 is journaled in a bracket 19 rising from a plate 20 which may be secured to the floor 14 of the deck by any suitable means, and preferably extends the entire length of the conveyer to take the wear incident to the forward movement of the fuel. The forward end of the shaft of the 65 conveyer 18 and the rearward end of the shaft of the conveyer 17 are journaled in brackets 21, 22, rising from an angle plate 23 fitting upon the forward end of the deck floor and the rearward end of the slope sheet. 70

The forward end of the shaft of the conveyer 17 is journaled in a bracket 24 rising from a plate 25 suitably secured to the slope sheet and extending backwardly the entire length of the conveyer. The forward end 75 of the shaft of the conveyer 16 is journaled in a bracket 26, rising from a plate 27 suitably secured to the floor of the fuel bin and extending backwardly the entire length of the conveyer. The rearward end of the 80 shaft of the conveyer 16 is preferably secured to the forward end of the shaft of the conveyer 17 by a universal joint 28.

The rearward end of the shaft of the conveyer 17 and the forward end of the shaft 85 of the conveyer 18 are provided with bevel gears 29, 30, which mesh with a similar gear 31 fixed upon a shaft 32 extending transversely across the tender, and to which power is applied for driving the several conveyers. Inasmuch as the direction of rotation of the conveyer 18 is the reverse of 90 that of the conveyers 16 and 17, its spiral flange is given a reverse direction relatively thereto. 95

A suitable motor is provided for driving the conveyers. Such a motor is conventionally shown at 33, and as being located at the forward end of the tender, its shaft 34 extending backwardly and being provided 100 with a bevel gear 35 which meshes with a pair of similar gears 36, 37, loosely mounted on the shaft 32. A double faced clutch 38, splined upon the shaft 32, provides means for locking either of the gears 36, 37, to the 105 shaft, and for reversing the direction of drive of the conveyers. The clutch member is controlled by a pull rod 39 extending for

wardly and in convenient reach of the fireman, this rod actuating a shipper yoke 40 in engagement with the clutch.

Where a plurality of sets of conveyers is employed, as shown, all are driven by means of the single shaft 32.

In order to protect the gearing from the fuel the brackets 21 and 22 take the form of a housing, including a cover plate 41.

- 10 When the tender is first loaded with fuel, the conveyer or conveyers will be entirely submerged therein and by their action will advance the lower fuel stratum, the upper portion of the load settling down as the advance movement is continued. The conveyers are preferably sufficiently close together so that substantially all of the fuel will be carried forward to the shoveling platform. Should any clogging occur the 15 direction of rotation of the conveyers may be reversed by shifting the clutch. The conveyers may be driven continuously, or may be operated intermittently either by the motor or clutch control.
- 20 While an operative and preferred form of construction is shown and described, various changes in detail may be introduced without departing from the scope of the invention.

25 I claim as my invention—

1. In a locomotive tender having a fuel bin provided with a floor and a slope sheet, in combination, a screw conveyer mounted on the floor, a screw conveyer mounted on 30 the slope sheet and delivering directly to the rear end of the first-named conveyer, and means for driving such conveyers.

2. In a locomotive tender having a fuel bin provided with a floor and a slope sheet, 40 in combination, a plurality of sets of aligned screw conveyers, the elements of each set being mounted, respectively, on the floor and slope sheet, the slope sheet conveyers delivering directly to the rear ends of the floor 45 conveyers, and means for driving such conveyers.

3. In a locomotive tender having a fuel bin and a fuel supporting deck back of the bin, in combination, screw conveyers mounted, respectively, on the rear wall of the bin and on the deck, and means for driving such conveyers.

4. In a locomotive tender having a fuel bin and a fuel supporting deck back of the 55 bin, in combination, a plurality of sets of aligned screw conveyers, the elements of each set being mounted, respectively, on the rear wall of the bin and on the deck, and means for driving the conveyers.

5. In a locomotive tender having a fuel bin with an inclined rear wall and a deck back of the bin, in combination, a screw conveyer mounted on the inclined wall, a screw conveyer mounted on the deck, a driving shaft having a bevel gear, and bevel gears

mounted on the shaft of each conveyer and meshing with the gear on the drive shaft.

6. In a locomotive tender having a fuel bin with an inclined rear wall and a deck back of the bin, in combination, a plurality 70 of screw conveyers mounted on the inclined wall, a plurality of screw conveyers mounted on the deck, the several conveyers being provided with bevel gears, and a driving shaft having gears meshing with the gears 75 of the conveyers.

7. In a locomotive tender having a fuel bin with an inclined rear wall and a deck back of the bin, in combination, a plurality 80 of screw conveyers mounted on the inclined wall, a plurality of screw conveyers mounted on the deck, the several conveyers being provided with bevel gears, a driving shaft having gears meshing with the gears of the conveyers, and screw conveyers mounted on 85 the floor of the bin and jointed to the conveyers mounted on the inclined wall.

8. In a locomotive tender having a fuel bin, in combination, a screw conveyer mounted on and in proximity to the fuel supporting wall of the bin, and means for driving 90 the conveyer in either direction.

9. In a locomotive tender having a fuel bin, in combination, a plurality of screw conveyers located upon and in proximity to 95 the fuel-supporting floor, and means for driving the conveyers in either direction.

10. In a locomotive tender having a fuel bin provided with a floor and a slope sheet, in combination, screw conveyers 100 mounted on the floor and slope sheet, and means for driving such conveyers in either direction.

11. In a locomotive tender having a fuel bin provided with a floor and a slope sheet, 105 in combination, a plurality of sets of aligned screw conveyers, the elements of each set being mounted, respectively, on the floor and slope sheet, and means for driving such conveyers in either direction.

12. In a locomotive tender having a fuel bin and a fuel supporting deck back of the bin, in combination, screw conveyers mounted, respectively, on the rear wall of the bin and on the deck, and means for driving such 115 conveyers in either direction.

13. In a locomotive tender having a fuel bin and a fuel supporting deck back of the bin, in combination, a plurality of sets of aligned screw conveyers, the elements of each 120 set being mounted, respectively, on the rear wall of the bin and on the deck, and means for driving the conveyers in either direction.

14. In a locomotive tender having a fuel bin with an inclined rear wall and a deck 125 back of the bin, in combination, a plurality of screw conveyers mounted on the inclined wall, a plurality of screw conveyers mounted on the deck, the several conveyers being provided with bevel gears, a driving shaft hav- 130

ing gears meshing with the gears of the conveyers, a motor, and reversible clutch mechanism for connecting the motor with the drive shaft.

5 15. In a locomotive tender having a fuel bin with an inclined rear wall and a deck back of the bin, in combination, a plurality of screw conveyers mounted on the inclined wall, a plurality of screw conveyers mounted 10 on the deck, the several conveyers being provided with bevel gears, a driving shaft having gears meshing with the gears of the conveyers, screw conveyers mounted on the floor of the bin and jointed to the conveyers 15 mounted on the inclined wall, a motor, and

reversible clutch mechanism for connecting the motor with the drive shaft.

16. A locomotive tender having a fuel bin provided with a slope sheet, a screw conveyer mounted on the slope sheet, and means 20 for driving the conveyer.

17. A locomotive tender having a fuel bin provided with a floor and a slope sheet at the rear end of the floor, a screw conveyer mounted on the slope sheet, means for advancing fuel over the floor of the bin, and means for actuating such conveyer and advancing means. 25

NATHAN M. LOWER.
